UNITED STATES PATENT OFFICE.

PAUL DAIMLER, OF CANNSTATT, GERMANY, ASSIGNEE TO THE FIRM OF DAIMLER-MOTOREN-GESELLSCHAFT, OF UNTERTURKHEIM, NEAR STUTTGART, GERMANY.

ARMORED AERIAL MACHINE.

1,098,785.

Specification of Letters Patent. Patented June 2, 1914.

Application filed February 20, 1914. Serial No. 820,940.

To all whom it may concern:

Be it known that I, PAUL DAIMLER, subject of the King of Wurttemberg, residing at 87 Waiblingerstrasse, Cannstatt, Kingdom of Wurttemberg, Germany, have invented certain new and useful Improvements in Armored Aerial Machines, of which the following is a specification.

This invention relates to propeller-driven armored aerial machines and constitutes an improvement in or modification of the invention set forth in the specification of my copending application for a United States Patent Serial No. 785,084 filed August, 16, 1913, in which the propeller shaft of the aerial machine is made hollow to receive a gun which may be discharged through the propeller shaft in the direction of flight, the propeller shaft being of sufficiently large internal diameter to enable the barrel of the gun to be adjusted therein for sighting purposes. This arrangement, however, permits of only a limited movement of the barrel of the gun within the hollow propeller shaft. The object of the present invention is to enable the gun not only to be discharged through the hollow propeller shaft, but also to be so directed as to discharge the projectile outside the periphery of the propeller blades thereby considerably increasing the range of the gun.

According to the present invention the gun is arranged in alinement with the axis of the hollow propeller shaft and behind the latter so that it is capable of being adjusted at such an angle to the axis of the propeller shaft as to be directed outside the periphery of the propeller blades.

Preferably in order that the range of the gun is not limited by the intervention of the motor, that is to say, in order to enable the gun to be directed in any direction outside the periphery of the propeller blades, the gun which is arranged in alinement with the propeller shaft and behind the latter is located between the propeller shaft and the motor, the motor power shaft being for this purpose extended outwardly toward the propeller. This arrangement enables the gun to be discharged in any direction laterally of the propeller blades, that is to say, either upwardly, downwardly or toward either side.

In the accompanying drawings two embodiments of the present invention are illustrated by way of example.

Figure 1 is a somewhat diagrammatic side view of the motor, propeller and gun, parts thereof being shown in section. Fig. 2 is a similar view to Fig. 1 showing the arrangement of the gun intermediate the propeller shaft and motor. As shown on Fig. 1 of the drawings the motor *a* drives the power shaft *b* which in turn transmits motion to the hollow propeller shaft *c* through the transmission gearing *d*, *f*. The hollow shaft *c* is of comparatively short length and carries at one end the propeller *e*. The gun *g* is arranged behind the hollow propeller shaft *c* so as to be normally in alinement with the axis thereof, the gun *g* being mounted in any suitable manner in a swivel bearing *i* concentric with the axis of the propeller shaft *c*.

As indicated by the shaded circle *A* in Fig. 1 of the drawings the gun *g* is capable of being adjusted at a slight angle to the axis of the propeller shaft *c* so as to permit of the sighting of the gun through the propeller shaft, while the shaded triangular portion *B* indicates the range of the gun outside the periphery of the blades of the propeller *e*.

It will be clear from reference to Fig. 1 that the range of the gun outside the periphery of the propeller blades is limited to some extent by the motor *a*, but, as illustrated in Fig. 2, this may be overcome by extending the motor shaft *b* toward the propeller *e* so that the gun *g* may be mounted in a position intermediate the motor *a* and the hollow propeller shaft *c*, so that in this case the gun *g* may be directed in any direction outside the periphery of the propeller blades, as indicated by the shaded portion *B'* in Fig. 2.

I claim:

1. In a propeller-driven armored aerial machine, the combination with a hollow propeller shaft carrying the propeller, of a gun arranged behind said shaft and in alinement with the axis thereof, said gun being adapted to be adjusted at an angle to said axis, thereby enabling the gun to shoot either through said shaft or at such an angle as to shoot outside the periphery of the propeller blades.

2. In a propeller-driven armored aerial machine, the combination with a hollow propeller shaft carrying the propeller, of a gun arranged behind said shaft and in alinement

with the axis thereof, and a swivel bearing for said gun for enabling the gun to be adjusted at an angle to said axis, whereby the gun may be directed either to shoot through 5 said shaft or at such an angle as to shoot outside the periphery of the propeller blades.

3. In a propeller-driven armored aerial machine, in combination, a motor having its power shaft extended toward the propeller,

10 a hollow shaft driven from the extended end of said power shaft and carrying the propeller, and a gun located in alinement with the axis of said hollow shaft and intermediate said hollow shaft and motor, said gun being adapted to be adjusted at an angle to 15 said axis to enable it to be directed to shoot either through said hollow shaft or outside the periphery of the propeller blades.

4. In a motor-driven armored aerial ma-

chine, in combination, a motor having its 20 power shaft extended toward the propeller, a hollow shaft driven from the extended end of said power shaft and carrying the propeller, a gun located in alinement with the axis of said hollow shaft and intermediate 25 said hollow shaft and motor, and a swivel bearing for said gun for permitting adjustment of the gun at an angle to said axis to enable it to be directed to shoot either through said hollow shaft or outside the 30 periphery of the propeller blades.

In testimony whereof I have affixed my signature in presence of two witnesses.

PAUL DAIMLER.
